UNITED STATES PATENT OFFICE.

MERWIN FOWLER, OF MERIDEN, CONNECTICUT, ASSIGNOR TO EDWARD MILLER, OF SAME PLACE.

IMPROVED SPRING-CATCH FOR LAMP-CHIMNEYS.

Specification forming part of Letters Patent No. 35,649, dated June 17, 1862.

To all whom it may concern:

Be it known that I, MERWIN FOWLER, of Meriden, in the county of New Haven and State of Connecticut, have invented a new and useful Improvement in Attaching Chimneys to Lamps; and I do hereby declare that the following is a full, clear, and exact description of the same, reference being had to the accompanying drawings, making a part of this specification, in which—

Figure 1 is a vertical central section of a lamp top and chimney, the latter being attached to the former according to my invention; Fig. 2, a plan or top view of the same.

Similar letters of reference indicate corresponding parts in the two figures.

This invention consists in securing the chimney to the lamp-top by means of a hook which is attached to the lamp-top and has a spring connected to it, and all arranged in such a manner that the hook will, under the action of the spring, press down upon the flange of the chimney and firmly secure the latter to the cone of the burner.

The object of the invention is to obtain a chimney catch or fastening which will not only secure firmly the chimney to the lamp-top and admit of the former being readily attached to and detached from the latter, but which will also possess the advantage of being secured to the lamp-top without cutting away any portion of the latter to admit air into the chimney or burner—a result which attends all of the spring catches or fastenings which have passed under my observation.

To enable those skilled in the art to fully understand and construct my invention, I will proceed to describe it.

A represents a lamp top or burner, which may be constructed in the ordinary way, and B the chimney, provided with a flange, a, at its bottom, as usual.

C is a hook of the form commonly termed

“hawk-bill.” (See Fig. 1.) This hook is attached to an axis, b, the ends of which are fitted in lugs or projections c c on the upper edge of the lamp-top and allowed to turn freely therein. The axis b has a spiral spring, d, attached to it, one end of which is secured to or bears against the burner. This spring has a tendency to keep the inner end of the hook C pressed down on the flange a of the chimney, whereby the latter is secured on the cone.

The hook C extends outward sufficiently far to admit of being readily depressed by the thumb or finger, so as to cause its inner end to be raised free from the flange in order to liberate the chimney, as shown in red outline in Fig. 1. By this arrangement it will be seen that no opening is formed in the lamp top or burner to admit air into the latter or into the chimney; hence the flame will only be supplied with air through the perforations designed for it. The invention therefore possesses all the advantages of the ordinary spring catches or fastenings without the disadvantage referred to, and it may be as cheaply applied as any of them, and is not liable to become deranged by use, which is the case with those fastenings having a spring and hook or catch combined in one piece, the spring being liable to become strained and bent out of proper position—a contingency which cannot occur in my invention.

Having thus described my invention, what I claim as new, and desire to secure by Letters Patent, is—

The combination of the hook C and spring d, applied to the lamp top or burner, substantially as and for the purpose herein set forth.

MERWIN FOWLER.
